UNITED STATES PATENT OFFICE.

JOHN E. MILLER, OF PITTSBURG, PENNSYLVANIA.

DESIGN FOR A VESSEL.

SPECIFICATION forming part of Design No. 22,114, dated January 10, 1893.

Application filed December 3, 1892. Serial No. 454,008. Term of patent 3½ years.

To all whom it may concern:

Be it known that I, JOHN E. MILLER, of Pittsburgh, in the county of Allegheny and State of Pennsylvania, have invented a new and original Design for Vessels, of which the following is a full, clear, and exact description, reference being had to the accompanying drawing, which shows in side elevation a vessel of glassware embodying my design.

10 The design consists in a vessel of glassware having surface corrugations, and having thereon a scroll pattern.

In the drawing, 2 represents the vessel, having vertical corrugations 3, and having thereon a scroll pattern 4.

15

I claim:—

The design for vessels substantially as herein shown and described.

In testimony whereof I have hereunto set my hand.

JOHN E. MILLER.
